Frank P. Mitten, Redlands, Calif.

Application May 25, 1949, Serial No. 2,869

Term of patent 14 years

(Cl. D64—12)

To all whom it may concern:

Be it known that I, Frank P. Mitten, a citizen of the United States and a resident of Redlands, county of San Bernardino, State of California, have invented a new, original, and ornamental Design for a Font of Three-Dimensional Display Letters, of which the following is a specification, reference being had to the accompanying drawing, forming part thereof.

The drawing shows perspective views of a font of three-dimensional display letters illustrating my new design, essential features of which are the rectangular and triangular openings formed in the closed or partially closed parts of the letters, the remaining letters being so formed as to carry out this scheme of angularity throughout the entire alphabet.

I claim:

The ornamental design for a font of three-dimensional display letters, substantially as shown and described.

FRANK P. MITTEN.
